(57) **CLAIM**

We claim the ornamental design for a tool box with drawers slidably mounted on rails for pickup truck, as shown and described.

DESCRIPTION

FIG. 1 is a perspective view of a tool box with drawers slidably mounted on rails for pickup truck showing our new design;

FIG. 2 is a front elevational view thereof;

FIG. 3 is a right side elevational view thereof, the left side elevational view thereof being a mirror image thereof;

FIG. 4 is a rear elevational view thereof;

FIG. 5 is a bottom plan view thereof;

FIG. 6 is a top plan view thereof; and,

FIG. 7 is a side view of the tool box with drawers slidably mounted on rails shown in its position of use at the rear of a pickup truck with a drawer shown open and with one of the rails removed for ease of illustration. The broken line depicts environmental structure for illustrative purposes only, forming no part of the claimed design.
